TOY

Eugene A. Hornberger, North Berger, N. J.

Application October 23, 1944, Serial No. 559,944

2 Claims. (Cl. 46—81)

This invention relates to improvements in toys and has for its object to provide means for projecting an airplane. Another object of the invention is to provide a toy air rocket driving device.

A further object of the invention is to provide a spring operated projector for launching a toy air rocket.

Other features and advantages will become more readily apparent from the following description and the accompanying illustrated drawings in which:

Figure 1 is an elevational view of my device, Figure 2 is an end view, looking from the line 2—2 of Figure 1,

Figure 3 is a top plan view of toy air rocket, Figure 4 is a longitudinal sectional view of the device shown with an operating spring contracted,

Figure 5 is an end view of Figure 4,

Figure 6 is a top plan view of the device,

Figure 7 is a detail elevational view of a projected device, and

Figure 8 is a section on line 8—8 of Figure 5.

Like reference characters indicate like parts throughout the following specification and in the drawings in which 10 indicates my toy, which consists of a longitudinal cylinder 11 provided with a slot in the top throughout its length and indicated at 12. The end of said cylinder is closed by plug 13, having secured to its inner surface a resilient cushion 14. Screw threaded on its opposite end is a cap 15, having a central aperture 16, through which a rod 17 is slidable, fixed on the inner end of the rod 17 is a disk 18, having an extension tongue 19, extending through the slot 12. Coiled upon the rod 17, within the cylinder, is a spring 20, and fixed to the outer end 21 of said rod 17 is a handle disk 22.

23 indicates an air rocket glider comprising a body 24 and wings 25 and 26; secured to the body 24 is a strap 27 terminating at its under end 28 in a clip of sufficient spring tension to en-

gage the tongue 19 and be held in place thereon temporarily. 29 is a handle by which the device may be held while being operated.

In operation the member 24 is attached to member 19 and the rod 17 drawn outwardly in order to compress the spring 20 and upon release of the handle 22 said spring will drive the members 18 and 19 forward with considerable force until stopped by the cushion 14, the impact of which will overcome the tension of the clip 28 and the member 24 will be driven into the air.

The body 24 of the air rocket may be coated with a luminous paint, if desired, in which case its flight will be discernible in the dark.

15 It is thought that persons skilled in the art of which this invention relates will be able to obtain a clear understanding of the invention after considering the description in connection with the drawings. Therefore, a more lengthy 20 description is regarded as unnecessary.

Minor changes in shape, size and rearrangement of details and parts, such as come within the purview of the invention claimed, may be resorted to in actual practice if desired.

25 I claim:

1. A device as described consisting of a cylinder split from end to end, caps on the ends of the cylinder, a spring in the cylinder, a plunger for contracting the spring, a disk on one end of the spring having a tongue extending through the split and a glider detachably connected to the said tongue.

2. A device as described consisting of a cylinder split from end to end, caps on the ends of the cylinder, a spring in the cylinder, a plunger for contracting the spring, a disk on one end of the spring having a tongue extending through the split and a glider detachably connected to the said tongue, and a cushion attached to the forward cap, said plunger projecting through an opening in the rear stop.

EUGENE A. HORNBERGER.
